UNITED STATES PATENT OFFICE.

CHARLES W. BECK, OF NEW YORK, N. Y., ASSIGNOR, BY MESNE ASSIGNMENTS, TO ELECTROLITE GAS LAMP COMPANY, OF NEW YORK, N. Y.

ACETYLENE-GAS GENERATOR.

SPECIFICATION forming part of Letters Patent No. 790,869, dated May 28, 1905.

Original application filed November 23, 1900, Serial No. 37,550. Divided and this application filed February 15, 1901. Renewed October 6, 1904. Serial No. 227,442.

To all whom it may concern:

Be it known that I, CHARLES W. BECK, of New York, county of New York, and State of New York, have invented certain new and useful Improvements in Acetylene-Generators, of which the following is a specification.

This invention relates to improvements in acetylene-generators, and refers more specifically to improvements in that type of generators wherein pulverulent carbid is fed in regulated quantities to a body of water, the rate of feed being automatically governed and determined by the rate of consumption of the gas generated.

15 Among the salient objects of the invention are to provide a feed mechanism which in operation tends to keep itself clean and free from becoming encrusted with residue; to provide a feed mechanism the operative parts 20 of which are so protected and inclosed as to render it extremely free from liability of clogging in operation, while at the same time the moving parts are relieved from the greater part of the friction due to the weight of carbid tending to crowd into the feed mechanism; to provide a two-part feed mechanism 25 consisting of an open-ended tubular member and a device coacting therewith to close said tubular member to stop the feed of carbid; 30 to provide a construction wherein the carbid is fed through a tubular member having inlet-ports alternately carried into and out of register with the discharge-passage of the carbid-receptacle by the reciprocation of the tubular member, whereby the carbid is fed through 35 the latter; to provide a construction wherein the tubular member works through a packed or sealed opening, and in general to provide improved details of construction and arrangement in a device of the character referred to.

To the above ends the invention consists in the matters hereinafter described, and more particularly pointed out in the appended claims, and will be readily understood from 45 the following description, reference being had to the accompanying drawing, the single figure whereof represents in axial sectional view

a portable lamp provided with a preferred embodiment of my invention.

Referring to the drawing, the invention is 50 shown as embodied in a portable vehicle-lamp; but it is to be understood that while the invention is peculiarly well adapted for a generator of this type yet many of the features thereof, and, in fact, most of them, are 55 equally well adapted for embodiment in other types of generators.

In said drawing, 1 designates as a whole a lower liquid font or chamber, 2 an elevated carbid-hopper, and 3 a reduced connecting- 60 passage uniting the hopper and associated parts with the upper part of the font or liquid-reservoir, said reduced portion forming a chamber 4, within which are arranged parts of the feed mechanism and through which the 65 carbid is fed from the hopper to the generating-chamber or reservoir.

The lower body 1 may be of any preferred and suitable construction adapted to contain a suitable supply of liquid into which the 70 pulverulent carbid is dropped by the feed mechanism, and likewise the upper member or hopper 2 may be of any suitable form and preferably provided with a converging or hopper-shaped lower end wall 5, which directs 75 the carbid to the feed-opening 6 in the bottom thereof.

In the preferred construction shown herein the cylindric contracted portion 3 is permanently attached to the lower part of the carbid-hopper concentrically with the feed-aperture thereof and is detachably connected with the upper portion of the reservoir or generating-chamber conveniently by being provided with an externally-threaded lower end portion 80 7, which is constructed to engage a correspondingly-threaded tubular portion 9 of a casting 8, forming the uppermost portion of said generating-chamber. Said casting 8 conveniently and as herein shown is provided with an internal annular shoulder 10 immediately below the internally-threaded portion thereof, upon which is arranged to rest a packing-ring 11, against which the lower end

of the threaded part 7 impinges to form a gas-tight joint.

14 designates as a whole a hollow valve-rod or feed-plunger arranged to reciprocate vertically through the aperture 6 of the hopper, said plunger preferably consisting of a hollow cylindric tube-like body open at its lower end and united at its upper end with an operating-stem 15 by means of a pair of arms 15', 10 the openings into the upper end of the plunger between said connecting-arms forming valve-ports for the entrance of the carbid to the plunger.

16 designates a cylindric housing or sleeve 15 connected at the upper end with the top wall 17 of the hopper or with other suitable support and arranged to depend thence downwardly, so as to inclose the feed-stem and upper end portion of the feed-plunger when the 20 latter is in elevated position, said housing 16 being made of an internal diameter somewhat greater than the external diameter of the feed-plunger, so as to afford a free working annular space 18 between said parts and terminating 25 at its lower end at a sufficient distance above the lower end of the hopper or feed-aperture to permit the pulverulent carbid to flow freely downwardly past said lower end and through the feed-aperture when the plunger 30 is lowered position, so as to permit such feeding operation. The housing 16 forms a part of the two-part feed mechanism and serves to close the parts in the tubular feed plunger when the latter is raised by the inflation 35 of the gas-bag. The feed-plunger 14 is arranged to work through a yielding diaphragm or gasket member 19, consisting of a soft-rubber ring having its inner margin, which rubs against the exterior of the feed- 40 plunger, made relatively thin or brought to a blunt knife-edge, so as to create as little frictional resistance as practicable and mounted within a cup-shaped casing 20 upon the lower end of the carbid-hopper. In order that the 45 ring may be compressed so as to reduce the diameter of its opening from time to time as it is worn away by the plunger, the casing 20 is provided with a lower end cap-ring 21, threaded thereon and having a portion 22, 50 which underlies the lower surface of the ring and is adapted to compress the latter within its housing as the ring is screwed farther upon the housing.

The feed-plunger is operated through the 55 medium of an expansible and collapsible gas-holder, designated as a whole 23 and located in the upper part of the hopper member above the partition 17 therein. Conveniently and as shown herein said gas-holder comprises an 60 inner rigid ring 24, mounted upon and secured to the partition 17, and a collapsible inverted-cup-shaped sheet-rubber member 25, having its lower margin secured to the exterior of the ring 24 by means of an outer clamp- 65 ing-ring 26, such a construction enabling the

upper side of the gas-holder or bag to descend or to collapse until it rests in contact with the bottom wall of the holder formed by the partition 17. Upon the upper side of the gas-holder is mounted a flat disk or rigid member 70 27, (forming in the present instance the bottom wall of a reducing-valve,) and with the center of this rigid disk 27 is connected the upper end of the stem of the feed-plunger. This connection is conveniently formed by 75 means of a nut 28, externally threaded to engage a correspondingly-threaded aperture in the lower side of the reducing-valve and provided with a radial, flange 29, which serves to clamp the margins of the aperture in the rubber bag through which said nut is inserted against the superposed disk, so as to form a gas-tight union, said nut being provided with a central aperture, threaded to receive the upper end of the feed-plunger stem, as indicated 80 at 30.

The gas-holder is deflated and the connected feed-plunger caused to descend into feeding position by the action of a spring thereon, said spring consisting in the present instance of a 90 coiled contractile spring 31, mounted upon the plunger-stem and having its upper end suitably connected with a nut or ring 32 upon the upper end of said stem and having its lower end connected with a relatively fixed 95 collar 33, mounted in the lower end of the tubular housing 16 and held against upward movement therein by means of a ledge or flange 34 upon the inner wall of the housing, with which a radially-extending portion or 100 flange 35 of said collar engages. The length of the feed-plunger and its relation to the gas-holder with which it is connected are such that as the upper side of the gas-holder approaches the lower limit of its movement— 105 *i. e.*, when it is nearly deflated—the upper end of the hollow feed-plunger is brought below the lower end of the tubular housing 16, and the carbid flows from the hopper into the hollow plunger and through the same. 110

A headlight (designated as a whole 36) is provided, which may be of any suitable or preferred construction, that shown herein consisting of an ordinary conical or bell-shaped chamber provided at its rear end with a suitable reflector and closed at its outer flaring end by means of a suitable lens 38, said headlight as a whole being conveniently supported from the main generator by means of a bracket 39, attached to the contracted waist portion 3 120 thereof, as indicated at 40. The bracket 39 is provided with a gas-passage 41, with one end of which the lower end of a pipe 42 communicates and with the opposite end of which communicates a burner-nozzle 43, projecting 125 upwardly within the headlight-chamber and terminating in a suitable burner-tip 44. The upper side of the headlight is provided with a suitable hood or chimney 45, which may be of any desired construction. 130

In order to provide for the passage of the gas from the generating-chamber to the burner, a tube 46 is arranged to extend through the bottom wall of the hopper into the chamber 4, rising at its upper end to a point within and near the upper wall of the hopper. Within the upper part of the hopper the gas is brought into contact or intimate relation with the body of carbid therein and is thus very effectually dried. From the upper part of the hopper the gas passes into the tubular housing 16 through apertures 47 and then upwardly through said housing into the gas-holder, passing from the latter into the hollow stem 15 of the feed-plunger through suitable apertures 48 and thence into the reducing-valve through a valve-controlled passage 49, which communicates with the reducing-valve, (designated as a whole 50.) Said reducing-valve is provided with a flat disk-shaped bottom which rests upon the upper side of the expansible gas-holder and with which the upper end of the stem of the feed-plunger is connected, as hereinbefore described. The interior of the reducing-valve body is divided by a flexible diaphragm 51, as usual, with the center of which is connected the stem of the valve 52, which controls the passage 49, hereinbefore referred to. The upper side of the valve 50 is provided with a stem 53, which extends out through an unthreaded opening in the top casing of the generator, said stem being threaded and provided with a nut 54, which may be adjusted downwardly upon the stem to hold the reducing-valve, and through its connection with the reducing-valve the feed-plunger, locked in uplifted position or adjusted upwardly into the position shown in the drawing, so as to permit the free reciprocation of the feed-plunger. From the lower chamber of the reducing-valve the gas passes out through a flexible tube or pipe 55, which is connected with the pipe 42, which leads downwardly to and communicates with the passage 41 of the headlight, as hereinbefore described.

The operation of the generator constructed as described will be obvious from the foregoing description, but may be briefly described as follows: Assuming that the generating-chamber and carbid-hopper, respectively, are supplied with suitable charges of liquid and pulverulent carbid, the generator may be brought into operation by simply moving the confining-nut 54 upwardly upon its stem, so as to release the feed-plunger and permit the latter to be forced downwardly by means of the expansion-spring, whereupon as soon as the inlet-ports of the plunger descend below the housing 16 the carbid will begin to flow into and through the plunger to the generating-chamber. When sufficient carbid has been dropped through the plunger to generate a volume of gas sufficient to inflate the gas-holder, the plunger will obviously be raised far enough to interrupt the flow of carbid therethrough, and vice versa. When enough gas has been consumed to deflate the holder sufficiently to lower the feed-plunger into feeding position, the carbid will again flow and generate more gas, and these operations will be repeated automatically as long as the consumption of gas continues.

While it is true that the hollow plunger forms no check to prevent the flow of gas (which will obviously be more or less moist) upwardly through the plunger, yet this gas will not reach the body of carbid within the hopper except through the very narrow annular space between the exterior of the plunger and interior of surrounding sleeve and through the gas-ports in said sleeve above the upper surface of the carbid. As to that portion of gas which reaches the carbid through the annular space surrounding the plunger the amount of carbid thus exposed is insignificant, and, furthermore, whatever carbid is thus acted upon will be the very first to be dropped in the next succeeding operation, so that there is no possibility of any considerable body of carbid becoming slaked and caked, so as to prevent free operation of the feed mechanism. Moreover, whatever particles of carbid adhere to the exterior of the plunger by reason of this slight slaking action within this annular space will be immediately rubbed off by the frictional engagement of the rubber ring 19 as the plunger descends, so that the feed mechanism will be kept entirely free and to all practical intents the gas will be excluded from the hopper except as it is admitted to the upper part of the hopper intentionally and for the purpose of drying it before it is admitted to the gas-holder. It is to be further noted that the engagement of the upper end of the plunger with the fixed ring or nut 33 serves to positively arrest the upward movement of the plunger before the latter rises far enough to carry its lower end above the rubber diaphragm-ring 19. By reason of the peculiar construction of the hollow plunger it will be seen that a relatively large and free feed-opening is provided for the escape of the carbid when the plunger is lowered, notwithstanding the operative parts of said feed mechanism are relatively small, and this is a feature of the utmost importance in a generator of this character, for the reason that it is extremely difficult to secure uniform feeding of the pulverulent carbid unless such free escape be provided.

While I have herein throughout the description referred to that member which controls the flow of carbid from the hopper to the generating-chamber as a "feed-plunger," it will be obvious that it constitutes, in effect, a valve member and is thus referred to in the broader claims on this feature. It will be obvious that this feature of the invention in particular is capable of wide application

and is not in any sense limited to a generator of the portable type or of the type herein set forth; but, on the contrary, it is capable of adaptation to any generator wherein pulverulent carbid is fed to a saturating-chamber. I do not, therefore, wish to be limited to the details of construction set forth herein except as the same are made the subject of specific claims.

10. I claim as my invention—

1. In a carbid-feed mechanism, the combination with a carbid-receptacle provided with a feed-aperture, of an open-ended tubular feed-plunger or valve member working through said feed-aperture and adapted to control the flow of carbid from the receptacle through the tubular plunger, whereby when the plunger is depressed carbid will flow into its upper end.

2. In a carbid-feed mechanism, the combination with a carbid-receptacle provided with a feed-aperture, of a tubular feed-plunger or valve member working through said aperture, and a relatively fixed member within the hopper arranged to close the inlet end of the plunger to arrest the flow of carbid therethrough.

3. In a carbid-feed mechanism, the combination with a carbid-receptacle provided with a feed-aperture, of a vertically-arranged tubular feed-plunger or valve member working through said aperture, and a relatively fixed tubular housing arranged to inclose the upper end of the feed-plunger when the latter is elevated.

35. 4. In a carbid-feed mechanism, the combination with a carbid-receptacle provided with a feed-aperture, of a vertically-arranged tubular feed-plunger or valve member working through said aperture, and a relatively fixed tubular housing of larger internal diameter than the external diameter of the upper end of the feed-plunger, and arranged to telescope over a substantial portion of the length of said plunger when the latter is elevated, whereby 45 the inlet end of the plunger remains closed throughout a substantial portion of its movement.

5. In a carbid-feed mechanism, the combination with a carbid-receptacle, provided with a feed-aperture, of a tubular feed-plunger or valve member working through said aperture, means coöperating with the upper end of the feed-plunger to control the flow of carbid therethrough, and a gasket provided with a yielding interior through which said feed-plunger operates and whereby its exterior is wiped.

6. In a carbid-feed mechanism, the combination with a carbid-receptacle provided with a feed-aperture, of a tubular feed-plunger or valve member working through said feed-aperture, having an exterior portion of extended length of uniform cross-sectional area, a tubular housing supported above said valve

member with its lower end arranged to telescope over the upper portion of the plunger when the latter is in elevated position, a relatively fixed gasket-ring surrounding said feed-plunger located at a substantial distance below the lower end of said housing and having frictional engagement with the exterior of said plunger, and mechanism operating automatically by the pressure of gas generated to reciprocate said plunger.

7. In a carbid-feed acetylene-generator, the combination with a lower saturating-chamber, an upper carbid-hopper provided in its bottom wall with a feed-passage arranged to discharge into said saturating-chamber, of means for automatically controlling the flow of carbid from the hopper to the saturating-chamber, comprising a tubular feed-plunger or valve member working through said feed-passage, a tubular housing arranged concentrically with the feed-plunger within the hopper and having its lower end arranged to telescope over the upper end of the feed-plunger when the latter is in elevated position, an operating-stem connecting with the said feed-plunger and extending up through said tubular housing, an expandible and collapsible gas-holder operatively connected with the upper part of said operating-stem whereby the inflation and deflation of said gas-holder actuates the feed-plunger, a spring arranged to act upon said gas-holder to deflate the latter, and a yieldable gasket surrounding the lower part of the feed-plunger and frictionally engaging its exterior, as and for the purpose set forth.

8. In a carbid-feed acetylene-generator, the combination with a lower saturating-chamber, an upper carbid-hopper provided in its bottom wall with a feed-passage arranged to discharge into said saturating-chamber, of means for automatically controlling the flow of carbid from the hopper to the saturating-chamber, comprising a tubular feed-plunger or valve member working through said feed-passage, a tubular housing arranged concentrically with the feed-plunger within the hopper and having its lower end arranged to telescope over the upper end of the feed-plunger when the latter is in elevated position, an operating-stem connecting with the said feed-plunger and extending up through said tubular housing, an expandible and collapsible gas-holder operatively connected with the upper part of said operating-stem whereby the inflation and deflation of said gas-holder actuates the feed-plunger, a spring arranged to act upon said gas-holder to deflate the latter, and a yieldable gasket surrounding the lower part of the feed-plunger and frictionally engaging its exterior, and means for locking said feed mechanism in closed position.

9. In an apparatus for generating acetylene gas, a feed mechanism having, in combination, a carbid-holder provided with a discharge-

opening, and a hollow open-ended valve-rod passing through said opening provided with one or more ports to register therewith, substantially as described.

5 10. In a carbid-feed mechanism, the combination with a carbid-receptacle provided with a feed-aperture, of an open-ended tubular feed-plunger or valve member working through said feed-aperture, means coöperating with the upper end of the feed-plunger to control the flow of carbid therethrough.

11. In a generator for producing acetylene gas, the combination with a lower saturating-chamber, an upper carbid-chamber provided 5 with a feed-aperture in its bottom wall, an open-ended tubular feed-plunger working through said feed-aperture, means coöperating with the upper end of the feed-plunger to control the flow of carbid therethrough and means operated by pressure of the gas generated for moving the plunger.

12. In a carbid-feed mechanism the combination with a carbid-receptacle, of an open-ended tubular valve member through which carbid flows to the generating-chamber, and means coöperating with said tubular valve member to control the flow of carbid therethrough.

13. In a carbid-feed mechanism the combination with a carbid-receptacle, of an open-ended tubular valve member extending into the carbid-hopper above the bottom thereof and through which carbid flows to the generating-chamber, and means coöperating with

said tubular valve member to control the flow 35 of carbid therethrough.

14. In a carbid-feed mechanism the combination with a carbid-receptacle provided with a feed-aperture, a tubular valve member working in said aperture, and means coöperating 40 with one end of said tubular valve member to control the flow of carbid therethrough.

15. An acetylene-gas generator comprising a carbid-hopper, an expansible and collapsible gas-holder, a two-part feed mechanism 45 consisting of a tubular valve member whose upper end extends into the carbid-holder through the bottom thereof and through which the carbid is fed, and a closure device for said tubular valve member, operative connections between one of the parts of the two-part feed mechanism and the gas-holder whereby when said holder is inflated the flow of carbid 50 through the tubular valve member will be stopped.

16. In a carbid-feed mechanism the combination of a carbid-receptacle provided with a feed-aperture of a tubular feed-plunger or valve member working through said feed-aperture and provided with one or more ports 60 to register therewith, and means coöperating with said feed-plunger to control the flow of carbid therethrough.

CHARLES W. BECK.
